ELECTRICAL FACIAL MASK

Stephen Duma, Staten Island, N. Y.

Application May 1, 1946, Serial No. 666,272

3 Claims. (Cl. 128—402)

1

This invention relates in general to a facial mask and in particular to a facial mask adapted to apply a heating beauty treatment to a human face.

It is an object of this invention to provide a facial mask for applying a heating beauty treatment to a human face.

More specifically, this invention proposes a facial mask adapted and shaped to conform with a human face and to apply a gentle heating treatment thereto.

The invention further proposes a facial mask comprising a flexible sheet material shaped to conform with a human face and having heating means mounted therein for applying a gentle beautifying heat treatment and having face-fitting or massaging members mounted therein for pressing and shaping contours in the face being treated.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a side elevation of a facial mask according to one form of this invention.

Fig. 2 is a front view of the article shown in Fig. 1.

Fig. 3 is a side cross section of the article shown in Fig. 2, taken along the line 3—3.

Fig. 4 is an enlarged cross section of a portion of the mask shown in the previous figures, taken along the line 4—4 of Fig. 3.

Fig. 5 is an enlarged cross section of a section of one layer of the mask shown in the previous figures during an intermediate step in its manufacture.

Fig. 6 is a similar view of the same portion after a further step in its manufacture.

Fig. 7 is a schematic front view of the article shown in the previous figures, outlining the formation of the heating member therewithin.

Fig. 8 is an enlarged fragmentary cross section of a portion of the facial mask according to a further form of the invention, the mask having an adjustable contour member thereon.

Fig. 9 is a detail vertical sectional view, taken on line 9—9 of Fig. 8, looking in the direction of the arrows.

Referring to the figures in detail, there is shown a mask generally designated 10 adapted to fit snugly and massagingly over the face of a wearer during or after a beauty treatment, adapted to apply a beauty heating treatment to the face of the wearer. The mask is shaped in the outline of a human face, having contours thereon to fit a forehead 11, nose 12, lips 13, and chin

2

14, and having securing straps or bands 15 for removably and adjustably mounting the mask on a wearer's face. There are also provided nostril openings 16 in the nose portion of the mask, and 5 optionally additional eye holes 17 and a mouth opening 18. An electric heating member 20 passes through the mask in a predetermined pattern, and an electric lead cord 21 serves to connect the heating member to a source of electric current.

The mask 10 is constructed in at least two layers; an outer structural layer 22 which is flexible and elastic, being adapted to stretch or contract to fit the exact contours of the face of a wearer and being adapted to hold the mask in 15 a substantially predetermined shape; and an inner, spongy layer 23 adapted to fit comfortably against the wearer's face and to conform closely with minor irregularities of the face and to cushion the mask against the face.

The heating member 20 is mounted entirely within the outer layer 22 and the inner layer is maintained even and regular in thickness except for face molding pad members 24 thereon 20 which are adapted and positioned to match desired facial contours.

The mask, as shown in the figures, is shaped to extend substantially across the entire face of the wearer and substantially back on the sides 30 of the face, terminating in securing bands 15 which are adapted to extend behind the back of the head. On two of the bands 15 are located buckles 26 or the like, and on the other two bands are openings 25 adapted to fasten to the 35 buckles thereby securing the mask to the face of the wearer. At predetermined positions on the face of the mask 10 are located face molding pad members 24 which are adapted to fill out the mask at selected positions such as near 40 the eyes and nose of the mask, and positioned to fill out hollows in the cheek of the wearer. These contour members are optionally positioned to conform with the contours of the average wearer; alternatively, the contour members are 45 positioned in an accurately determined pattern according to an individual study of a particular wearer for whom the mask is designed.

The heating member 20 is positioned in the outer layer of the mask in substantially horizontal lines, weaving back and forth horizontally across the face of the mask. This heating member is an insulated electric resistance wire, so selected that it produces a low local heat, sufficient to warm the face of the wearer but not high enough 55 to cause uncomfortable heat. A control device such as a thermostatic control (not shown) may be added to the mask heating system to control the heat therein.

The mask 10 is constructed by forming two 60 rubber or rubber-like mask face pieces 28 (see

Fig. 5) of substantially identical outline, shaped to fit the face as desired. The heating member 20 is disposed between these two face pieces in the pattern shown in Figs. 3 and 7. The face pieces are then pressed together and subjected to a vulcanizing heat according to known processes, whereby the two pieces 28 are molded together to form one unitary piece 22 containing the heating member 20 substantially in its center. This piece 22 is then used for the outer layer of the finished mask. A sponge material 23 is mounted on the inside of this mask structure by means of an adhesive 30 or the like which bonds the two layers together. In this way, the inner sponge layer is retained substantially wrinkle free within the mask and is adapted to provide a smooth and pleasant surface to the face. The inner or sponge layer extends substantially across the entire mask, except for the bands 15 which comprise only the outer layer 22.

The mask is used in a manner which is apparent from the figures. The mask 10 is fitted over the face of the wearer, preferably with a beauty cream base applied to the face, and the mask is adjusted for size by tightening bands 15 until a proper fit is obtained. If necessary, the mask is pulled locally or otherwise adjusted to cause it to fit smoothly over the entire facial surface. The heating unit is then energized, warming the mask and the face until the desired degree of heat is produced. The heat, enclosed in the substantially moisture proof mask causes an almost immediate perspiration and opening of facial pores; the moisture thus produced in itself gives an effect somewhat resembling the effect of a localized Turkish bath. This moist warmth is an ideal final step in a beauty treatment.

In Figs. 8 and 9 there is shown a movable contour member 24^a adapted to be used on the mask 10 shown in the previous figures. According to one form of the invention, these contour members may be integral portions of the inner spongy layer 23 of the mask. According to a further form of the invention, these contour members 24^a as shown in Figs. 8 and 9 are adapted to be placed on the inner surface of the mask. The contour member 24^a comprises a pad-like member 31 shaped to conform with the desired facial contour. Along one surface of this member is a layer of a non-tacky adhesive, whereby the pad 24^a may be removably secured to the inner surface of the mask. Thus, the contour member 24^a may be placed on the mask by pressing the adhesive surface against layer 23, and used for a heat treatment for one person in a beauty parlor. Subsequently, the member 24^a is removed and repositioned for another customer.

Due to the horizontal arrangement of the electrical heating wires, as shown in Fig. 7, no heating wire crosses any head opening of the user, and the heating wires are disposed across the usual vertical facial wrinkles on the sides of the nose and mouth, to induce maximum circulation through these areas.

The electrical heating wires are embedded between the plies of the outer layer of material which makes up the facial mask, so that no wire is dependent upon any local insulation, and complete safety is thus assured the wearer. The plies of the outer mask layer are united by vulcanization so that exposure of any heating wire is virtually impossible.

While I have illustrated and described the preferred embodiments of my invention, it is to be understood that I do not limit myself to the pre- 75

70 cise constructions herein disclosed and the right is reserved to all changes and modifications coming within the scope of the invention as defined in the appended claims.

5 Having thus described my invention, what I claim as new and desire to secure by United States Letters Patent is:

1. A facial heating mask comprising a rubber mask shaped to fit the contours of a human face, 10 having openings for a nose, eyes, and mouth, having adjustable bands for securing said mask on the face of a wearer, having a heating member disposed in a pattern in horizontal lines parallel to said openings across the area of the mask, said mask comprising an outer structural layer and an inner padding layer extending across substantially the entire facial area of said outer layer and terminating short of the adjustable bands thereon, said heating member being disposed substantially midway between the surfaces of the outer layer, said padding being flexible and compressible to conform with the contours of the face of a wearer, said padding layer being secured to said outer layer substantially across the entire area thereof by means of an adhesive layer, and movable contour members removably secured to the inner surface of said mask and adapted to conform with desired facial contours.

2. A facial heating mask comprising a rubber mask shaped to fit the contours of a human face, 20 having openings for a nose, eyes, and mouth, having adjustable bands for securing said mask on the face of a wearer, having a heating member disposed in a pattern in horizontal lines parallel to said openings across the area of the mask, said mask comprising an outer structural layer and an inner padding layer extending across substantially the entire facial area of said outer layer and terminating short of the adjustable bands thereon, said heating member being disposed substantially midway between the surfaces of the outer layer, said padding being flexible and compressible to conform with the contours of the face of a wearer, said padding layer being secured to said outer layer substantially across the entire area thereof by means of an adhesive layer, and movable contour members removably secured to the inner surface of said mask and adapted to conform with desired facial contours.

3. A facial heating mask comprising a rubber mask shaped to fit the contours of a human face, 30 having openings for a nose, eyes, and mouth, having adjustable bands for securing said mask on the face of a wearer, having a heating member disposed in a pattern in horizontal lines parallel to said openings across the area of the mask, said mask comprising an outer structural layer and an inner padding layer extending across substantially the entire facial area of said outer layer and terminating short of the adjustable bands thereon, 40 said heating member being disposed substantially midway between the surfaces of the outer layer, said padding being flexible and compressible to conform with the contours of the face of a wearer, said padding layer being secured to said outer layer substantially across the entire area thereof by means of an adhesive layer, movable contour members removably secured to the inner surface of said mask and adapted to conform with desired facial contours, and said contour members comprising a shaped padding member having a non-tacky adhesive across one surface thereof.

4. A facial mask having an outer layer of yielding insulation material molded to fit the face of the user and provided with openings for the eyes, nose and mouth matching those of the user, an electrical heating unit embedded in said outer layer and extending across said mask in horizontal lines parallel to said openings and spaced therefrom, face molding pads detachably secured to the inner surface of the mask, and adjustable means for securing the mask to the face of the user to vary the pressure of the same against the user's face.

65 STEPHEN DUMA.
